DESIGN FOR AN END PIECE FOR SPEC- TACLES OR SIMILAR ARTICLES

Edwin Reynolds, Vineland, N. J.

Application February 3, 1934, Serial No. 50,605

Term of patent 14 years

To all whom it may concern:

Be it known that I, EDWIN REYNOLDS, a citizen of the United States, residing at Vineland, in the county of Cumberland and State of New Jersey, have invented a new, original, and ornamental Design for an End Piece for Spectacles or Similar Articles, of which the following is a specification, reference being had to the accompanying drawing, forming part thereof.

Fig. 1 is a perspective view of the outside of

an end piece for spectacles or similar articles showing my new design;

Fig. 2 is a perspective view of the inner side; and

Fig. 3 is an end view from the rear of the same.

I claim:

The ornamental design for an end piece for spectacles or similar articles, substantially as shown.

EDWIN REYNOLDS.
